(57) **CLAIM**

The ornamental design for an access control device, as shown and described.

DESCRIPTION

FIG. 1 is a front, left side, bottom perspective view of a first embodiment of an access control device showing our new design;

FIG. 2 is a front view thereof;

FIG. 3 is a right side view thereof;

FIG. 4 is a left side view thereof;

FIG. 5 is a top view thereof;

FIG. 6 is a bottom view thereof;

FIG. 7 is a front, left side, bottom perspective view of a second embodiment of the access control device;

FIG. 8 is a front view thereof;

FIG. 9 is a right side view thereof;

FIG. 10 is a left side view thereof;

FIG. 11 is a top view thereof; and,

FIG. 12 is a bottom view thereof.

The broken lines in the drawings illustrate portions of the access control device that form no part of the claimed design. The wavy broken lines in FIGS. 7-12 are for the purpose of illustrating portions of the access control device with a symbolic break in its length.

All surfaces now shown form no part of the claimed design.
